AIR FEED FOR DIVING SUITS

Ernst Töpper, Berlin-Neukölln, Germany, assignor
of one-half to William Hamilton Martin, Lon-
don, England

Application November 24, 1937, Serial No. 176,334
In Germany November 28, 1936

9 Claims. (Cl. 61—70)

This invention relates to air feed devices, for diving suits of the general kind in which a helmet is attached by flange or like means to the shoulder and neck part of the rest of the suit.

5 An object of the invention is the provision of air feed means which will not unduly inconvenience the diver by readily fouling obstacles.

A further object is the provision of air feed means which ensure more or less uniform ventilation within the helmet.

10 A further object is the provision of air feed means which are positioned in a more convenient manner than hitherto.

15 Yet another object is the provision of an improved connection between the helmet and the rest of a diver's suit. Further objects may become apparent when the invention has been understood from the following description.

In existing arrangements, it is usual to provide 20 a stub-pipe or spigot projecting from the helmet and to connect the airline thereto; this arrangement has drawbacks, chiefly in that it is easily fouled by obstacles, which are overcome by the present invention.

25 The invention is illustrated in one example, in the accompanying diagrammatic drawing, in which:

Figure 1 is a rear elevational view of a helmet with its joint in section.

30 Figure 2 is a broken plan view of a shoulder-piece and associated parts.

Figure 3 is an enlarged sectional view of an assembled joint.

In the drawing the helmet 1 is shown having 35 an attachment flange 2 which has say three holes in it for the passage of securing bolts. The shoulder-piece 3 of the diving suit also has a flange 4 similarly perforated for bolts. The flanges 2 and 4 are channelled as shown at 2A and 4A respectively, so that they are in effect 40 hollow and have air chambers in them. These chambers communicate with the bolt perforations. The chamber 2A is open to the interior of the helmet 1 through a slot at 5, but preferably 45 has its channel overlapped by an annular rim of metal 6 for the purpose of deflecting incoming air upwardly and uniformly into the helmet, rather than projecting it straight against the diver's face or neck. The flange 4 has its chan- 50 nel or chamber closed by the upper edge of the shoulder-piece 3. To the shoulder-piece there may be attached through the medium of bars 3A, usual ballast weights such as the slab of lead 7. Projecting downwardly and outwardly from the 55 flange 4 is a boss 8, the hollow interior of which

communicates with the chamber 4A openly. Secured in this boss is an air spigot 9 which has a union nut 10 serving to connect to the union 9 an elbow pipe 11, to which there is again connected by the union 12 the airline 13. The unions at 10 and 12 are preferably such as to permit rotation. A spring-loaded non-return valve 14 is provided within the boss 8 to prevent escape of air backwards up the airline or out of the suit, should a union such as 10 fail or the airline be broken. 10 The flanges 2, 4 are assembled together by the passage through their perforations of tubular bolts 15 capped by blind nuts 16 which preferably have yieldable sealing washers 16A. The bore of a bolt 15 communicates by radial holes with the chambers 2A, 4A. Between the flanges 2 and 4 there are nipped the rubber flange 17 of the diver's suit and also, preferably, a flat rubber washer or gasket 18, 17 and 18 being perforated for the bolts 15. 20

The helmet is thus attached to the body part of the suit by means of a joint which can be made completely air- or water-tight, and which at the same time serves to transmit through itself the whole of the air supplied to the interior of the suit by the airline 13. The channel 2A opening all round the helmet gives an even or uniform entry of air and a member such as 6 if provided, deflects that air so as to avoid objectionable air currents. The attachment of the airline 13 to 30 the flange 4 is inconspicuous and can readily enable the airline 13 to lead down the diver's back and side where if desired it may be naturally held in the hand or loosely attached, for example, to a waist-belt. 35

What I claim is:

1. In a diving suit, the combination of a hollow helmet flange, a hollow flange on the body portion, and hollow interattaching means for said flanges, the whole thereby acting as an air pas- 40 sage.

2. In a diving suit, the combination of a hollow helmet flange, a hollow flange of the body portion, and hollow bolts to pass through perforations of said flanges for mechanically interattaching them 45 and forming air passages therebetween.

3. In a diving suit, the combination of a hollow helmet flange, a hollow flange on the body portion, hollow bolts to form a connection between said flanges, and a third flange of the flexible 50 part of the suit adapted to be nipped between said hollow flanges.

4. In a diving suit, the combination of a hollow helmet flange, a hollow flange of the body portion, hollow bolts for interconnecting said flanges, and 55

valved airline connection means to the second of said flanges.

5. In a diving suit, the combination of a helmet, a flange therefor of channel section opening inwardly into said helmet, a rigid shoulder-piece, a channelled flange on said shoulder-piece, a flexible body portion, a flange on said body portion being adapted to lie between said first and second flanges, an airline union to the second of said flanges, and hollow interattachment means passing through all said flanges and forming air passages therebetween.

10 6. A device as claimed in claim 5, in which said helmet flange is provided with an internal deflecting element across its channel.

15 7. In combination, a diving helmet, a channel-sectioned securing flange rigid with said helmet, a rubber body portion, an outwardly extending flange formed integrally with said body portion around the neck thereof, a metal rigid shoulder-

piece, an outwardly extending hollow flange rigid with said shoulder-piece, air union means to connect an airline to said flange of said shoulder-piece, hollow bolts with radial holes to interattach and interconnect said helmet and said shoulder-piece flanges and blind nuts for said bolts.

5 8. In a diving suit, a helmet, a connecting flange on the helmet, said flange having an air passage therein with a substantially continuous 10 opening into the interior of the suit, and connecting means including a hollow bolt extending through the flange and formed with a port which communicates with the passage, the hollow bolt also serving as a conduit for air to the interior 15 of the flange.

9. A construction as defined in claim 1, wherein the hollow helmet flange opens uniformly into and around the helmet.

ERNST TÖPPER. 20
